UNITED STATES PATENT OFFICE.

WILLIAM G. BROWNE, OF KINGSTON, NEW YORK.

ICE-PICK.

SPECIFICATION forming part of Letters Patent No. 690,829, dated January 7, 1902.

Application filed November 23, 1900. Serial No. 37,486. (No model.)

To all whom it may concern:

Be it known that I, WILLIAM G. BROWNE, a citizen of the United States, residing at Kingston, in the county of Ulster and State of New York, have invented certain new and useful Improvements in Ice-Picks; and I do declare the following to be a full, clear, and exact description of the invention, such as will enable others skilled in the art to which it appertains to make and use the same.

The invention relates to ice-picks.

The object of the invention is to provide an improved form of ice-pick blade by means of which ice may be more expeditiously cut or chipped.

With this object in view the invention consists in certain features of construction and combination of parts, which will be herein-after more fully set forth.

In the accompanying drawings, Figure 1 is a perspective view of one form of my improved ice-pick. Fig. 2 is a longitudinal sectional view. Fig. 3 is a cross-sectional view through the blade of the pick. Fig. 4 is a longitudinal sectional view illustrating a modification of the invention, and Fig. 5 is a cross-sectional view of a modified form of blade.

Referring to the drawings, Figs. 1, 2, and 3, the numeral 1 denotes the handle of the pick, and 2 its blade. The blade is preferably formed of steel, and it is constructed in angular form, either semicircular or V-shaped, as shown in Figs. 3 and 5. The edges of the blade toward the end thereof contract or decrease to form a concave conical-shaped pointed end. The edges of the blade are made flat, as shown at *a*, whereby the blade can be grasped by one hand without injury to the same for the purpose of cracking a piece or lump of ice held in the other hand by means of the handle of the implement. The handle, as shown in Fig. 1, is made of an approximately ball-shaped outer end *b*, whereby to give weight thereto when cracking of the ice is to be accomplished. The interior or central portion of the handle has formed therein an angular longitudinal recess which is substantially of the same construction as that shown by the rear portion of the blade, which

is mounted in said recess, the inner end of which abuts against a shoulder *a'* at the terminus of the recess. In Fig. 2 I show the handle made in sections, the semicircular recess being formed in one section concave and the other convex, the two sections, with the inclosed part of the blade, being secured together by means of pins or bolts *a a'*, passing through the two sections and through said inclosed part of the blade.

The pick may be used like the ordinary pick and will reduce to a minimum the liability of it slipping or flying off to one side in striking downwardly or at right angles to the surface of the ice. Owing to the peculiar shape of the blade it is well adapted for shaving or chipping off the ice. In doing this of course the blade of the pick is leaned down against the ice until it is substantially parallel to the surface thereof and is reciprocated.

In Fig. 4 I have shown my invention applied to a hammer-handle—a handle which is reciprocated independently of the blade and which imparts blows or shocks thereto to force the same through the ice.

In Fig. 5 the blade is shown of V-shaped cross-section.

From the foregoing description, taken in connection with the accompanying drawings, the construction, operation, and advantages of my invention will be readily understood without requiring an extended explanation.

The device is exceedingly useful for the purpose for which it is designed and may be placed upon the market at a comparatively small cost.

Various changes in the form, proportion, and the minor details of construction may be resorted to without departing from the principle or sacrificing any of the advantages of this invention.

Having thus fully described my invention, what I claim as new, and desire to secure by Letters Patent, is—

In an ice-pick, the combination with the handle having an approximately ball-shaped outer end, said handle constructed in sections, one of which is concave, the other convex, whereby to form a semicircular recess between said sections, of a semicircular blade,

having flat edge portions mounted in the recess formed by said concave and convex sections, and pins or bolts for securing said sections and the blade together, and the operating end of the blade being contracted or decreased whereby to form a concave conical-shaped pointed end, substantially as specified.

In testimony whereof I have hereunto set my hand in presence of two subscribing witnesses.

WILLIAM G. BROWNE.

Witnesses:

ROBERT H. CUBBERLY,
DU BOIS G. ATKINS.
